US00D608635S

(12) **United States Design Patent**
Blick

(10) **Patent No.:** **US D608,635 S**
(45) **Date of Patent:** **** Jan. 26, 2010**

(54) **SLIDE BOX**

(75) Inventor: **Kevin David Blick**, Tokyo (JP)

(73) Assignee: **British American Tobacco Japan, Ltd.**,
Tokyo (JP)

(**) Term: **14 Years**

(21) Appl. No.: **29/326,416**

(22) Filed: **Oct. 17, 2008**

Related U.S. Application Data

(62) Division of application No. 29/284,001, filed on Aug.
29, 2007, now Pat. No. Des. 580,751.
